UNITED STATES PATENT OFFICE

CHARLES J. MILLER, OF MINNEAPOLIS, MINNESOTA

TABLE

Application filed October 9, 1925, Serial No. 61,493. Renewed June 2, 1932.

My invention relates to a folding type of table adapted for use generally as a table, but particularly designed for kitchens, small dining rooms, breakfast nooks, or wherever it may be desired to conserve floor space.

The primary object of the invention is to provide a table of simple compact construction which without detracting in any way from the general appearance of the furniture in the room, will be capable of folding into a comparatively small space and be unfolded easily and quickly when desired for use.

A further object is to provide a folding table that is adapted when folded to receive or contain or have hinged to the legs of the table, the seats or settles used around it when unfolded.

A further object is to provide a simple inexpensive, automatic means for bracing the hinged sections of the table when unfolded and holding them rigidly in their expanded or open position.

A further object is to provide means becoming automatically operative when the table is folded to serve as legs to hold the folded section of the table from touching the floor when in an upright position.

A further object is to provide a folding table of solid construction with provision for automatically bracing all of the joints and particularly in providing edge rails in such form and arrangement to allow the folding features of the table, while at the same time bracing the top sections against splitting or warping.

A further object is to provide a table embodying a folding principle of such a nature that the table, or table and seats, may be of a single or double construction according to the space where it is to be used and the requirements of such use.

Other objects of the invention will appear from the following detailed description.

The invention consists generally in various constructions and combinations all as herein-after described and particularly pointed out in the claims.

In the accompanying drawings forming part of this specification,

Figure 1 is a perspective view of a single fold type of table in an open position with the seats or settles ready for use;

Figure 2 is a similar view showing the seats in a nested position beneath the table;

Figure 3 is a perspective view showing the table and seats folded;

Figure 4 is a view of the under side of the table top showing the means for locking it in its expanded or open position;

Figure 5 is a sectional view on the line 5—5 of Figure 4;

Figure 6 is a similar view showing the table partially folded;

Figure 7 is a vertical sectional view showing the table completely folded and the position assumed by the locking devices when the table is in this position;

Figure 8 is a sectional view on the line 8—8 of Figure 4;

Figure 9 is a vertical sectional view showing the means employed for supporting one side of the folded table;

Figure 10 is a perspective view showing a type of the table without the settles or seats in an open or unfolded position;

Figure 11 is a vertical sectional view showing the type of table illustrated in Figure 10 in its folded or closed position;

Figure 12 is an end view of a table and seats having a double fold or one having folding sections on each side of a middle stationary section;

Figure 13 is a similar view showing the same type of table without the use of the seats or settles.

In the drawings, 2 represents a section of a table top having supporting legs 3 and braced and strengthened on the under side in the usual manner. 4 is an extension of the top section 2 having one edge hinged thereto as at 5 and adapted when unfolded to form a horizontal continuation of the top 2 and when folded to drop down to a vertical position parallel substantially with the legs 3.

The top section 4 has legs 6 hinged to the under side of the section 4 at 7, and joined together at their upper ends by an end rail 8 adapting the legs 6 to be folded inwardly and upwardly against the under side of the table

top or rails when the table is to be closed and downwardly to a vertical position when the table is opened. As shown in Figure 4, the edge rail 8^a opposite the rail 8 is preferably 5 longer than the rail 8 and the side rails 8^b and 8^c of the two sections 2 and 4 are offset or out of alignment with each other so that the sections can be folded without interference of the opposite rails, but at the same time these 10 rails will perform their functions of bracing and strengthening the table sections and preventing them from warping or twisting. I thus am able to provide a table comprising folding sections which will not only be of simple construction, but strong and durable 15 and will not become loose and rickety in the joints and be unfit for use as a table.

A block 9 is secured to the under side of the top section 2 and a similar block or bar 20 10 is correspondingly secured to the under- 25 side of the top section 4 opposite the block 9 on the other side of the hinges 5 therefrom. A brace 11, preferably A shaped in form, is hinged at 12 to the bar 8 and has a beveled inner end 13 provided with an orifice 14 to receive a pin 15 in the block 10 for the purpose of locking the legs 6 in their unfolded position. A bar 16 is hinged at 17 to the block 9 and has an orifice 18 to receive a pin 19 30 mounted in the block 10 and adapted to hold the table sections 2 and 4 in their aligned open position, bridging the hinges 5 between the sections while the A shaped brace 11 bridges the hinges 7 between the legs 6 and the table 35 top 4.

A tension member 20 composed preferably 40 of spring wire has a looped end passing through a slot 21 in the bar 16 and engaging the block 10 bearing on the end of the bar 16 and normally holding it in its interlocking engagement with the pin 19 with a yielding pressure. The other end of the spring member 20 engages a stud 20^a in the block 10 near the brace 11 and bearing on the end of the 45 brace serves to hold it in yielding engagement with the pin 15. Thus I utilize one spring for locking both of the hinged braces of the table. The bar 16 has a beveled end 22 and a lever 23 is loosely mounted on a pin 24 and projects through an opening 25 under the top of the section 4 to a position where it can be most conveniently grasped to release the bar 16. The inner end of this lever bears 50 on the block 10 and also contacts with the brace 11 so that when the outer end of the lever is raised the brace 11 will be disengaged from the pin 15 thereby releasing or unlocking the legs 6, and allowing them to be folded inwardly and upwardly against the table 55 top.

When the legs 6 are so folded, the brace 11 being disengaged from the pin 15, will slide on the under surface of the block 10 being guided by the tension member 20, and engage 60 the beveled surface 22 of the bar 16 and such

engagement will operate to move the end of the bar downwardly and disengage it from the pin 19, thereby releasing the lock between the two sections of the table and allowing the section 4 to swing down to a vertical position parallel substantially with the legs 3. This movement is clearly illustrated in Figures 5 and 6; Figure 5 showing the unfolded position of the parts with the sections and the legs in their locked position while Figure 6 shows the legs released or unlocked and the sliding brace 11 in the act of disengaging the bar 16 from the pin 19 to allow the section 4 to be swung down to a vertical position as shown in Figure 7.

To fold the table, it will only be necessary, therefore, for the user to raise the lever 23 which trips the brace 11 and the act of closing or folding the legs 6 will operate automatically to unlock the bar 16 and allow the top sections to be folded and the table closed.

Upon opening the table, the withdrawal of the brace 11 by the lowering of the legs will release the bar 16 and allow the tension of the spring 20 to move the bar to its locking position, thereby holding the two top sections in perfect alignment. At the same time, when the legs reach a vertical position, the brace 11 will engage the pin 15 and become automatically locked until such time as it is again disengaged by the movement of the lever 23.

To provide a support for one side of the table when folded and prevent the table top from contacting with the floor, I provide supplementary legs 26 hinged at 26^a to the top section 2 and having their free ends projecting through openings 27 in the end rail of the section 4. These legs are pivoted off the center of or eccentric to the pivots of the section 4 and consequently when the top section 4 is down to the vertical position as shown in Figure 9, the legs 26 will be projected or protruded through the openings 27 to a point beyond the edge of the top section and will be substantially the length of the legs 3 and will cooperate therewith to support the folded table in an upright position. Obviously, when the sections are unfolded, the supplementary legs 26 will be 105 retracted within the openings 27 and in this position will have the function of bracing the sections of the table in a horizontal aligned position and preventing downward collapsing or sagging of the sections when 110 in use. The preferred arrangement of these supplementary legs 26 is shown in Figure 4 wherein the table is illustrated in its open or unfolded position and the supplementary legs are retracted and aid in bracing and 115 supporting the table top.

The legs 3 are provided with hinged connections 28 between them and seats or settles 29 and 29^a, these hinged connections comprising pin and eye members which adapt 120

the seats to be raised with the table when the top section is lifted or the seats may be lifted independently of the table top and readily disengaged from the legs. The 5 hinged connections adapt the seats to be swung inwardly under the table top and one section is preferably a little longer and higher than the other so that they will assume a nested position as indicated in Figure 2 when 10 folded under the table top. When the table has been unfolded it will only be necessary to reach under the top and swing the seats outwardly on their hinges to a usable position.

15 Figure 3 illustrates how compactly the table may be folded with the seats occupying the space under the narrower table top section and the wider section forming in effect a leaf depending vertically in front of 20 the table and concealing the space beneath the top and the hinged seats. These top sections may of course be made of suitable material that will take a high polish or finish and even when the table is folded the mechanism employed in the folding operation will 25 be concealed and the table will form an ornamental piece of furniture in the room.

The table shown in Figures 1 to 4 has a wider top section 2 adapting it to receive the 30 nested seats or settles. In some instances I may omit these seats and in that case, the table with a narrower top section 2^a, shown in Figure 10, may be provided, the other elements of the table being substantially as hereinafter described with reference to the table of Figure 1. This construction, with the narrower top section, permits a more compact folding of the table as illustrated in Figure 11 where the section 4 swung down 40 to a vertical position is close to the legs 3 of the section 2^a and the table may of course in this form be put in a smaller space than where provision is made for the nesting of the seats under the table top.

45 In Figure 12, I have shown a table corresponding to the one illustrated in Figure 1 except that it has a double fold construction, a normally stationary middle top section 30 being provided with centrally arranged legs 3^a and end sections 4 on each side corresponding to the section previously described except that instead of having one section on one side of the stationary top section, provision is made for a hinged section 50 on both sides, thus practically doubling the surface area of the table top when unfolded. Provision is here made for the nesting of two pair of seats, one pair of seats on each side of the legs 3^a instead of one pair of nested 55 seats as shown in Figure 3. The means for locking the hinged sections in their open or unfolded positions is substantially the same as described with reference to previous figures and further illustration or description 60 herein is unnecessary.

In Figure 13, a double folding table is shown in which the middle or stationary section 30^a, is narrower to adapt the table for use without the nesting seats, the hinged end sections being thereby brought close to the 70 central legs 3^a during the folding operation.

The form of table illustrated in Figure 13 will effect an economy in space of five-sixths of the area required for this type of table when in its open position. The table sections may of course be made of any suitable material and finished in any preferred manner, and in various ways the details of construction herein shown and described may be modified and still be within the scope of my 80 invention.

It will be noted that the bars 16 and 26 both lie across the hinge line and are pivoted on the same side of the hinge line and respectively act as bracers to resist buckling 85 action at the hinge line either upwardly or downwardly.

I claim as my invention:

1. A table comprising sections hinged together for relative movement and having supporting legs, the legs of one section being adapted to swing inwardly and allow that section to turn down to a vertical position parallel substantially with the legs of the other section, and supplemental legs slidably 95 arranged and connected to one of the sections in a manner to be automatically projected to supporting position as the swinging section travels to folded position.

2. A table comprising sections hinged together for relative movement and having supporting legs, the legs of one section being adapted to fold to allow that section to turn down to a vertical position, and means normally retracted but adapted to be projected by the turning down of said section to contact with the floor and cooperate with said section to support that side of the table when folded.

3. A table comprising sections hinged together for relative movement and having supporting legs, the legs of one section being adapted to fold and allow that section to swing down to a vertical position, and bars mounted to reciprocate in said swinging section and pivoted eccentric to the axis of said section whereby when said section is swung to its vertical position, said bars will be projected to contact with the floor and cooperate with said swinging section to support the 115 table.

4. A table comprising top sections hinged together for relative movement and having supporting legs, the legs of one section being pivoted, means hinged to the legs, and yieldably urged toward one of the sections, and adapted for latched engagement therewith for locking said pivoted legs in an upright supporting position when the table is open, and a lever adapted to be manually operated 125 130

for unlatching said locking means to allow the folding of said legs and table.

5. A table comprising top sections hinged one upon the other, a bar, adapted for locking said sections in horizontal alignment, legs for one section pivoted thereon, a brace movable with the legs and adapted for latch engagement with one of the sections for holding said legs in their upright supporting position, a tension member for holding both bar and brace in their locking position, and said brace being adapted when released and moved by the legs to disengage said bar, from its locking position.

15. 6. A table comprising top sections relatively hinged and having supporting legs, one pair of legs being pivotally mounted, a bar pivoted to one of the sections, and adapted for locking said top sections in horizontal alignment, a brace for locking said pivoted legs in a vertical position, means yieldably urging said bar and brace to locking position, a manually operated means for releasing said brace, and said brace being adapted 25 when said pivoted legs are folded to engage said bar and move it to its release position.

7. A device of the class described comprising two hinged together top sections, one section having legs pivoted to fold therebeneath, a brace hinged to the foldable legs and detachably engageable with one section to latch the legs in supporting position, a bar hinged to one of the sections and detachably engageable to secure the sections in table-forming position, a resilient element connected to one of the sections and yieldably engaging brace and bar in a manner to urge them to latch position, the brace being engageable with the bar to unlatch the same, as 40 the legs are folded.

8. A device of the class described comprising two legged, hinged together, top sections, first and second, the second having legs pivoted to fold therebeneath, a hinged brace movable with the legs and detachably engageable with said second section to latch the legs in supporting position, a bar hinged to the first section and detachably engageable with the second to secure the sections in 45 table-forming position, a resilient element connected to one of the sections and yieldably engaging brace and bar in a manner to urge them to latch position, the brace being engageable with the bar to unlatch the same as the legs are folded, and a means movably attached to one of the sections and having a portion arranged to unlatch the brace.

9. A device of the class described comprising two legged, hinged together, top sections, first and second, the second having legs pivoted to fold therebeneath, a brace hinged to the foldable legs, a pin beneath the second section engageable by the brace to latch the legs in unfolded position, a bar 60 hinged to the first section, a second pin on the

second section engageable by the bar to lock the sections in aligned open position, a tension member arranged to yieldingly urge the brace and bar to latch position, and a lever movably attached to one of the sections and having a portion arranged for releasing the bar against the action of the tension member, the brace being wedgingly engageable with the bar to unlatch the same as the legs are swung from supporting position.

10. A device of the class described comprising two-legged hinged together top sections, first and second, the second having legs pivoted to fold therebeneath, a hinged brace movable with the legs and detachably engageable with the second section to latch the legs in supporting position, a bar hinged to the first section and detachably engageable with the second to secure the sections in table-forming position, the brace being engageable with the bar to unlatch the same as the legs are folded.

11. A device of the class described comprising two legged hinged together top sections, first and second, the second having legs pivoted to fold therebeneath, a hinged brace movable with the legs and detachably engageable with the second section to latch the legs in supporting position, a bar hinged to the first section and detachably engageable with the second to secure the sections in table-forming position, the brace being engageable with the bar to unlatch the same as the legs are folded, and means operable by a simple lifting motion, to unlatch the brace.

12. A table comprising sections hinged together and having supporting legs, the legs of one section being adapted to swing inwardly and allow that section to turn down to a vertical position, supplemental legs arranged across the hinge line of the table sections and adapted to be automatically projected to supporting position as the swinging section travels to folded position, and a bar hinged to one section and detachably engageable with the other section and also arranged across the hinging line, said supplemental legs, and said bar acting respectively to prevent hinging movement at the hinge line in opposite directions.

13. A device of the class described comprising two legged hinged-together top sections, first and second, the second having legs pivoted to fold therebeneath toward the other legs across the hinge line, a hinged brace movable with the legs and detachably engageable with the second section to latch the legs in supporting position, and a bar hinged to the first section detachably engageable with the second to secure the sections in table-forming position.

14. A four-legged table consisting of, a top composed of two hinged together sections first and second, the length of the second measured in direction perpendicular to the

hinging axis being substantially equal to the over-all height of the table, and having a pair of legs hinged thereto, the first section having two fixed legs, the second section being adapted to be swung toward the fixed legs, and to a vertical position, and the hinged legs being adapted to be swung to a position parallel to the section to which they are attached when that section is in vertical position, means adapted to secure the top sections in coplanar table-forming relation, and means for locking the hinged legs in table-supporting position.

15. A four-legged table consisting of, a top composed of two hinged-together sections first and second, the length of the second measured in direction perpendicular to the hinging axis being substantially equal to the over-all height of the table, and having a 20 pair of legs hinged thereto, the first section having two fixed legs and being shorter than the second section in direction perpendicular to the hinging axis, the second section being adapted to be swung toward the fixed legs 25 and to a vertical position, and the hinged legs being adapted to be swung to a position parallel to the section to which they are attached when that section is in vertical position, means adapted to secure the top sections in 30 coplanar table-forming relation, and means for locking the hinged legs in table-supporting position.

16. A four-legged table consisting of, a top composed of two hinged-together sections 35 first and second, the length of the second measured in direction perpendicular to the hinging axis being substantially equal to the over-all height of the table, and having a pair of legs hinged thereto and adapted to 40 swing in unison, the first section having two fixed legs, the second section being adapted to be swung toward the fixed legs, and to a vertical position, and the hinged legs being adapted to be swung to a position parallel to 45 the section to which they are attached when that section is in vertical position, means adapted to secure the top sections in coplanar table-forming relation, and means for locking the hinged legs in table-supporting position.

50 In witness whereof, I have hereunto set my hand this 5th day of October 1925.

CHARLES J. MILLER.
